R. C. MINTON

ELECTRIC SWITCH

Filed April 9, 1924

UNITED STATES PATENT OFFICE.

RICHARD CALDWELL MINTON, OF EAST BOLDON, ENGLAND, ASSIGNOR TO A. REY-
ROLLE & COMPANY LIMITED, OF HEBBURN-ON-TYNE, ENGLAND, A BRITISH COM-
PANY.

ELECTRIC SWITCH.

Application filed April 9, 1924. Serial No. 705,330.

To all whom it may concern:

Be it known that I, RICHARD CALDWELL MINTON, a subject of the King of England, and residing at East Boldon, in the county 5 of Durham, England, have invented certain new and useful Improvements in Electric Switches, of which the following is a specification.

This invention relates to electric switches 10 and has particular reference to switches which control a number of resistance sections such as are used in starting and regulating dynamo electric machines. It is sometimes necessary for certain operations to be 15 performed such for example as the opening or closing of auxiliary circuits or the movement or control of interlocking mechanism at or near one or both ends of the travel 20 of the contact arm or equivalent member of a regulating switch.

In a switch according to this invention a 25 movable member is provided which is operated by the contact arm or the like when it is at or near the end of its travel, such 30 movable member remaining in its new position and leaving the contact arm free to be moved back. Preferably the movable member is restored to its original position when the contact arm is returned to its initial 35 place, that is to say the movable member is operated at each end of the travel of the contact arm.

In the accompanying drawings,

Figure 1 shows diagrammatically one construction of switch according to this invention, and

Figure 2 shows in perspective and by way of example a mechanical embodiment of a switch performing similar functions.

With reference first to Figure 1, A is the contact arm of a switch moving over contacts B between which are resistances C. Cooperating with this contact arm is a movable member somewhat like an inverted Y 45 in shape. This member is pivoted as at D and comprises two arms D' D² and a stem D³. The distance between the two arms D' and D² can be adjusted as by means of the screw E. The contact arm A or an insulated projection A' on it comes into cooperation with the end of the arm D' in its initial or starting position and with the end of the arm D² at or near the end of its travel. The

stem D³ of the inverted Y member carries a switch F controlling an auxiliary circuit 55 G and a second auxiliary circuit H is controlled by a switch J carried by the contact arm A itself.

A regulating switch of this kind is of particular advantage for use with a motor converter in an automatic or semi-automatic substation. It is desirable for such a machine to have two definite resistances in the field circuit, one for starting and the other for running and moreover for the regulating 65 switch to be capable of varying the resistance in the circuit with the field during running to vary the voltage of the machine.

These conditions are satisfied by connecting the resistance C as shown in Figure 1 in 70 series with the field coil M of a motor converter N and by connecting the ends of the auxiliary circuit G across a definite portion of the resistance C and the switch arm A. In the starting position of the switch the 75 gap in this auxiliary circuit G controlled by the switch F is closed as shown in Figure 1 and an auxiliary short-circuiting switch K is open. Thus the main portion of the resistance C is in circuit with the field coils of the converter. In this initial or starting position also the switch J closes a gap in the second auxiliary or starting 80 circuit H which, as shown in Figure 1, includes the solenoid P which operates the 85 main switch R controlling the A. C. supply mains S. The D. C. mains from the converter are shown at T.

When the machine is run up and synchronized the switch K is closed (preferably by the automatic operation of the rotor short-circuiting gear) and the main portion of the resistance C is consequently short-circuited. The first movement of the contact arm A away from its initial position breaks the second auxiliary or starting circuit H but further movement of the arm A has no effect until it reaches nearly the end of its travel for it is moving over the short-circuited resistance sections C. At that point 90 the contact arm reaches the contact B to which the end of the first auxiliary circuit G is connected and it then moves the arm D² and opens the switch F thus breaking the short circuit across the main portion of 100 the resistance but without altering the re-

sistance in the field circuit. The contact arm A may now be moved in the reverse direction to insert more of the resistances C into the field circuit and may be moved freely backwards and forwards to vary that resistance and regulate the voltage of the machine.

The auxiliary circuit H is shown as having a second gap controlled by a switch L which if opened would render the switch J 10 inoperative, but this switch L like the switch K do not form in themselves part of the present invention and are not particularly described.

Referring now to Figure 2 the contact arm A² of the switch is shown as mounted 15 on a spindle A³ capable of rotation by a hand wheel A⁴, this being a convenient and known type of construction. Instead of the switch J being mounted on the arm A² it is 20 operated by a projection A⁵ on the spindle A³ acting in conjunction with a spring-controlled lever J'. Again the switch F controlling the auxiliary circuit G is operated through a pivoted spring-controlled lever F' 25 having a plate F² on which are pins F³ and F⁴. The pin F⁴ projects downwards from the plate F² in the path of a projection A⁶ mounted on the spindle A³, this projection A⁶ acting on the pin F⁴ to close the switch. 30 The pin F³ projects upward from the plate F² in the path of another arm or projection A⁷ and these two members cooperate to open the switch F when the hand wheel A⁴ has been rotated to bring the switch arm 35 A² from its initial position as shown to the end of its travel, i. e. to the contact B' where the auxiliary circuit G to the left of Figure 2 is connected to the resistances C.

Figure 2 is given as showing a convenient 40 mechanical construction for a switch according to this invention suitable for fulfilling the functions described with reference to the switch shown diagrammatically in Figure 1.

In the case of an automatic substation previously referred to, arrangements are preferably made whereby the switch may be locked in its initial position when the station shuts down so that the gaps in the 45 circuits controlled by the switches J and F are closed. This locking may be accomplished in any convenient way say by mechanism which prevents the rotation of the hand wheel A⁴.

The description above given of the particular application of a regulating switch according to this invention is by way of example only.

The details of construction may be varied 60 and instead of the auxiliary circuits mentioned mechanical interlocking devices may be arranged operated by the switch arm or the mechanism which moves it at its initial and final positions. Again more than one 65 movable member operated by the switch arm

or its equivalent may be employed so that intermediate operating positions may be obtained.

What I claim as my invention and desire to secure by Letters Patent is:—

1. In a resistance-regulating switch the combination of a resistance, a plurality of contacts connected to said resistance in intervals or steps, a main contact-making member adapted to move over said contacts, an auxiliary switch adapted to be closed when the main contact-making member is in its initial position, and a second auxiliary switch adapted to be opened when the main contact-making member reaches the end of its travel 80 and to be closed when the main contact-making member is in its initial position.

2. In a resistance-regulating switch the combination of a resistance, a plurality of contacts connected to said resistance in intervals or steps, a main contact-making member adapted to move over said contacts, an auxiliary switch adapted to be closed when the main contact-making member is in its initial position and opened when the arm 90 is in any other position, a short circuiting circuit connected across a portion of the resistance and the main contact-making member and a second auxiliary switch in such circuit adapted to be closed when the main contact-making member is in its initial position and opened when said main contact-making member reaches the end of its travel.

3. In a resistance-regulating switch the combination of a resistance, a plurality of contacts connected to said resistance in intervals or steps, a main contact-making member adapted to move over said contacts, a starting circuit for a motor converter, an auxiliary switch in said starting circuit adapted to be closed when the main contact-making member is in its initial position and to be opened when the main contact-making member leaves that position, a circuit connected across a portion of the resistance and the main contact-making member, a second auxiliary switch in said circuit, acting when closed to short-circuit the portion of the resistance to which said circuit is connected, and means for opening said second auxiliary switch when the main contact-making member has passed over the short-circuited portion so that said portion can be brought into operation by a backward movement of the main contact-making member.

4. In a resistance-regulating switch the combination of a resistance, a plurality of contacts connected to said resistance in intervals or steps, a rotatable spindle, a main switch arm mounted on said spindle and adapted to move over said contacts, a starting circuit for a motor converter, an auxiliary switch in said starting circuit, an operative connection between the spindle and 125

said auxiliary switch acting to close said switch when the main switch arm is in its initial position, a spring acting to open said auxiliary switch when the main switch arm 5 leaves its initial position, a circuit connected to a portion of said resistance, a second auxiliary switch in said circuit, an operative connection between the spindle and said second auxiliary switch acting to close said 10 switch and short-circuit the connected portion of the resistance when the main switch arm is in its initial position, and an operative connection between the spindle and said second auxiliary switch acting to open said switch when the main switch arm has passed 15 over the short-circuited portion of the resistance so that the said portion can be brought into operation by a backward movement of the main switch arm.

In testimony whereof I have signed my 20 name to this specification.

RICHARD CALDWELL MINTON.
